(57) CLAIM

I claim the ornamental design for a fence member, as shown and described.

DESCRIPTION

FIG. 1 is a front perspective view of a fence member being of indeterminate length showing a first embodiment of my new design;

FIG. 2 is an enlarged end elevational view thereof;

FIG. 3 is a top plan view thereof, a bottom plan view being identical thereto;

FIG. 4 is a front elevational view thereof, a back elevational view being identical thereto;

FIG. 5 is a front perspective view of a fence member being of determinate length showing a second embodiment of my new invention; and,

FIG. 6 is an enlarged front elevational view thereof broken for ease of illustration.
